UNITED STATES PATENT OFFICE

GOTTFRIED GÄNG, OF USTER, NEAR ZURICH, SWITZERLAND

WRENCH

Application filed January 5, 1931, Serial No. 506,716, and in Germany October 25, 1930.

This invention relates to a wrench which can be employed as pipe wrench and also as bolt wrench, and is adapted to be used for different sizes of bolts and pipes.

5 This is attained according to the invention in that the wrench handle consists of a plurality of superposed plates rigidly connected together, oscillatable in a hollow wrench jaw body around a common pivot and terminate in tongues, some of which engage directly and the others through the intermediary of blades rotatably mounted in the wrench jaw body, in horn-like claws, and turn these claws in opposite directions around 10 their axle on the handle being turned, so that the jaw aperture formed by the claws narrows, and in this manner the work introduced between the claws is rigidly held thereby.

15 20 An embodiment of the invention is illustrated by way of example in the accompanying drawings in which:

Fig. 1 shows the wrench in side elevation.

Fig. 2 is a section on line 2-2 of Fig. 4.

25 Fig. 3 is a section on line 3-3 of Fig. 4.

Fig. 4 is a longitudinal section on line 4-4 of Fig. 1.

The handle of the wrench consists, apart from the cover plates *a* which can be omitted, 30 of a plurality of plates *b*, which are mounted in the milled out wrench jaw body *c* so that they can be turned around an axle *h*. The plates *b* terminate in tongues *d*, some of which engage directly and the others through 35 the intermediary of blades *e* in horn-like claws *f*. These claws are located in the wrench jaw body *c* at its jaw aperture *g*, whereas the blades *e* are rotatable mounted on an axle *h* in the body *c*. The claws *f* and 40 also the tongues *d* are connected by springs *i*, which tend to hold the claws *f* and plates *b* in the inoperative position. If a piece of work is inserted in the wrench jaw aperture 45 *g* and the handle oscillated in the direction of the arrow, shown in Fig. 1, the plate tongues *d* turn the claws *f* towards one another. Thus the aperture formed between 50 these claws is narrowed and the work rigidly gripped between the claws.

I claim:

A wrench, comprising in combination a handle composed of a plurality of superposed plates, rigidly connected together, a hollow jaw body, a common axle for said plates in said jaw body, horn-like claws in said jaw body, a tongue on the end of each of said plates some of said tongues engaging in a corresponding number of said horn-like claws, a pin in said jaw body, and intermediate blades one for each of said tongues not engaging directly with claws said blades oscillatably mounted on said pin engaging with the corresponding tongues and claws so that on said handle being turned said claws are oscillated around their axle, thereby narrowing the mouth of the wrench and gripping the work inserted therein.

In testimony whereof I affix my signature.
